ATTORNEY

UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed August 18, 1923. Serial No. 658,032.

To all whom it may concern:

Be it known that I, ALVIN D. KEENE, a citizen of the United States, and a resident of Pittsburgh, in the county of Allegheny and State of Pennsylvania, have invented a new and useful Improvement in Electric Furnaces, of which the following is a specification.

My invention relates to electric furnaces and particularly to electric resistor furnaces.

The object of my invention is to provide a relatively simple resistor mounting for an electric resistor furnace that shall permit of being easily placed in, and removed from, the furnace structure.

In practicing my invention, I provide a plurality of refractory heat-insulating walls enclosing a furnace chamber and supporting a plurality of spaced sets of refractory members, of substantially T-shape, projecting into the furnace chamber. The refractory members of T-shape are spaced apart in each set and each member is provided with a depression in one surface adjacent to the inner end thereof, and is provided in the other surface thereof with a longitudinally extending groove.

Relatively narrow and thin refractory plates, having laterally extending grooves in their inner surface, are held by adjacent members of T-shape, the ends of the grooved bars fitting into a depression and a groove respectively.

A relatively heavy resistor member performed to comprise a plurality of straight, substantially parallel-extending end connected convolutions is held by the grooved plates whereby the convolutions extend substantially parallel to the furnace walls and closely adjacent thereto. The resistor member is substantially self-supporting between and beyond the refractory grooved supporting plates or bars.

The device embodying my invention is closely related to and is an improvement upon the device disclosed in a co-pending application of T. A. Reid, Serial No. 584,620, filed August 28th, 1922, and assigned to the Westinghouse Electric & Manufacturing Company.

In the single sheet of drawings—

Figure 1 is a view, in vertical lateral sec-

tion, of an electric furnace embodying my invention,

Fig. 2 is a view in front elevation of the device embodying my invention, and

Fig. 3 is a view, partly in side elevation and partly in section, of the device illustrated in Fig. 2.

An electric furnace 11 comprises side walls 12, a bottom wall 13 and a top wall 14, each of which is constituted by a plurality of refractory bricks or blocks of suitable heat-insulating material.

An inner lining 15 for each of the walls may comprise a plurality of bricks or blocks of suitable refractory high-temperature resisting material, the hereinbefore described walls being suitably spaced apart to provide a furnace chamber 16 of any suitable or desired contour and dimensions.

In building up the inner layer 15 in the side end and top walls, a plurality of sets of elongated refractory supporting members 17 are located therein, symmetrically spaced both laterally and longitudinally of the supporting wall. Each of the members 17 extends a short distance into the furnace chamber 16 and is provided in one of its surfaces adjacent to the inner end thereof with a depression 18.

A longitudinally extending slot or groove 19 is provided in the opposite surface of the members 17 adjacent to the inner ends thereof of the member 17. The location of the groove and of the depression is such as to permit of locating therein the respective ends of a relatively narrow, elongated bar 21 which consists of a suitable refractory electric-insulating material.

A resistor member 22 comprises a plurality of integral, end-connected, substantially parallel-extending, straight convolutions of a suitable metallic resistance material, a portion of each convolution being located in laterally-extending grooves 23 provided in the bars 21. The convolutions of the resistor member 22 extend between and beyond the spaced bars 21 and are located parallel and closely adjacent to the inner surface of the lining 15 of the respective walls.

Any desired terminal construction may be employed for the individual resistor members 22, of which a plurality may be pro-

vided as may be desired or as may be found necessary, and such terminal construction is not illustrated or described in detail, as it forms no part of my invention.

5 In installing the resistor members 22, they may be held in substantially their proper operative positions against or closely adjacent to the walls, after which the bars 21 may be suitably placed in their proper operative position by first moving that end thereof that is to be located in a depression 18 so that this end will fit into the depression, while the other end thereof is located at a greater distance from the wall. By a 10 lateral tilting movement of the respective bars 21, relatively to the co-operating wall, they are then moved into their proper operative positions substantially as illustrated in Figs. 1 and 3 of the drawing, it being understood, of course, that the respective convolutions of the resistor members 22 are placed in the co-operating grooves 23 whereby the convolutions are supported at spaced intervals. As above stated, the resistor member 15 22 is made up of relatively heavy resistor material that is substantially self-supporting between and beyond the bars 21.

A lock or key 24 is provided in the groove 19 in front of the outer surface of the bar 21 to prevent any lateral movement of the bars relatively to the adjacent walls surface. While this key member 24 has been shown as of substantially U-shape, it may be of 20 L-shape, or other suitable shape, if desired.

35 Instead of providing a depression in one surface of each of the members 17 and a groove in the other surface thereof, I may provide a depression in each surface, one of the depressions being deeper than the other. The ends of the respective bars 21 fit into the depressions in the co-operating pairs of spaced members 17. One end of the bar 21 is placed into the deeper depression, and the bar is moved longitudinally of its length until it touches the bottom of the depression and the other end is then given a lateral movement until it can be dropped into the shallower depression. No locking key is required and 40 the bars 21 interlocked with the members 17 are held against a lateral movement either parallel to the face of the furnace wall or at right angles thereto. The bars 45 can be removed by a longitudinal and then a lateral tilting movement thereof.

In removing a damaged resistor, it is only necessary to remove the necessary number of key members 24, after which the bars 21 may be given a lateral tilting movement 50 away from the adjacent wall. The free resistor unit 22, which was supported by

these bars 21 may then be easily and quickly removed from the furnace structure and be replaced by a new heating unit.

Various modifications and changes may 65 be made herein without departing from the spirit and scope of my invention, and I desire, therefore, that only such limitations shall be imposed as are set forth in the prior art or in the appended claims. 70

I claim as my invention:

1. In an electric furnace, in combination, a plurality of refractory walls enclosing a furnace chamber, a plurality of spaced sets of refractory members supported by one 75 of said walls and having their inner ends projecting into said furnace chamber, the members of each set being located in aligned spaced relation relatively to each other, grooved resistor-supporting bars of refractory electric-insulating material extending between adjacent pairs of refractory members in each set and being placeable in operative position relatively thereto by a lateral tilting movement thereof, a resistor member 80 of relatively heavy and unyielding material supported by said grooved bars and extending between and beyond said bars, and means on one of said refractory members for holding a bar in its proper operative position. 90

2. In an electric furnace, in combination, a plurality of refractory walls enclosing a furnace chamber, a plurality of refractory members supported by one of said walls and projecting into said chamber, each member 95 having a depression in one surface and a longitudinally-extending open groove in the opposite surface, a laterally-grooved resistor-supporting bar extending between said refractory members and having its ends 100 located respectively in said depression and said groove, and means operatively engaging one of said refractory members for holding said bar in its proper operative position. 105

3. In an electric furnace, in combination, a plurality of refractory walls enclosing a furnace chamber, a plurality of spaced refractory members supported by one of said walls and having their inner ends projecting 110 into said chamber, and a resistor-supporting bar extending between said refractory members and interlocked therewith to prevent movement thereof parallel to the refractory wall and being placed in operative 115 position relatively thereto by a tilting and lateral movement thereof.

In testimony whereof, I have hereunto subscribed my name this 13th day of August, 1923.

ALVIN D. KEENE.
